NOVELTY UNICORN HORSESHOE OR THE LIKE

Jack P. McDaniel, Cumberland, N.C.
(514 Owen Drive, Fayetteville, N.C. 28304)

Filed Nov. 12, 1971, Ser. No. 198,499

Term of patent 14 years

Int. Cl. D21—01
U.S. Cl. D34—5 GP

FIG. 2

FIG. 1

FIG. 5

FIG. 4

FIG. 8

FIG. 7

FIG. 6.

FIG. 10

FIG. 9

FIG. 1 is a top plan view of the novelty unicorn horseshoe or the like showing my new design;

FIG. 2 is a bottom plan view of such shoe;

FIG. 3 is a rear elevational view of the same;

FIG. 4 is a front elevational view of such shoe;

FIG. 5 is a side elevational view of the same, the opposite side thereof being substantially identical thereto;

FIG. 6 is a top plan view of a modification of the unicorn shoe or the like of the present invention;

FIG. 7 is a bottom elevational view of such modification;

FIG. 8 is a rear elevational view of the same;

FIG. 9 is a front elevational view of such modification;

FIG. 10 is a side elevational view of the same, the opposite side thereof being substantially identical thereto;

FIG. 11 is a top plan view of an even further modification of the unicorn shoe or the like of the present invention;

FIG. 12 is a bottom elevational view of such modification;

FIG. 13 is a rear elevational view of the same;

FIG. 14 is a front elevational view of such modification;

FIG. 15 is a side elevational view of the same, the opposite side thereof being substantially identical thereto;

FIG. 16 is a top plan view of an even further modification of the unicorn shoe or the like of the present invention;

FIG. 17 is a rear elevational view of such modification;

FIG. 18 is a front elevational view of the same;

FIG. 19 is a side elevational view of such modification; and

FIG. 20 is a side elevational view of the same, the opposite side thereof being substantially identical thereto.

I claim:

The ornamental design for a novelty unicorn horseshoe or the like, as shown.
